UNITED STATES PATENT OFFICE.

BENJAMIN W. MARTIN, OF ZANESVILLE, AND HOMER SAMS, OF AKRON, OHIO.

MACHINE FOR PLACING WASHERS IN HEEL-MOLDS.

1,336,319.

Specification of Letters Patent.

Patented Apr. 6, 1920.

Application filed August 25, 1919. Serial No. 318,550.

To all whom it may concern:

Be it known that we, BENJAMIN W. MARTIN and HOMER SAMS, citizens of the United States, residing at Zanesville and Akron, in the counties of Muskingum and Summit, and State of Ohio, have invented new and useful Improvements in Machines for Placing Washers in Heel-Molds, of which the following is a specification.

This invention relates to means for applying the washers to the pins in the molds for forming rubber heels and the principal object of the invention is to provide means whereby said washers may be placed on a large number of sets of pins at one operation and with but a few movements of the parts.

Another object of the invention is to provide means for automatically feeding the washers to the point of delivery and in a position to be passed over the pins when the carrying means are lowered.

Another object of the invention is to provide means for releasing the washers, after being placed on the pins from the delivery means and at the same time releasing the locking means which hold the delivery means in the lowered position.

The invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:—

Figure 1 is a side view of the invention showing the lower part of the mold in section;

Fig. 2 is a sectional view;

Fig. 3 is a like view taken at right angles to Fig. 2;

Fig. 4 is a fragmentary plan view;

Fig. 5 is a sectional view of the curved tubes.

In these views 1 indicates the mold plate on which the shouldered pins 2 are arranged in groups. This plate is provided with the recesses 3 one of which is located on each corner thereof for receiving the legs of my improved device. This device consists of a rectangular frame 4 which at each corner is

provided with the depending part 5 and each part has adjustably secured thereto the leg 6 which has a rounded end for engaging the recess 3. When the legs are placed in the recesses the device will be properly positioned in respect to the mold plate. The upper edge of the frame has an upwardly depending flange 7 and this flange forms a rectangular recess in which is located a plate 8. This plate is normally held in a raised position above the bottom of said recess by means of the spring plungers 9 carried by the frame. The plate 8 is provided with an upwardly extending flange 10 which is located an appreciable distance from each of its side edges and said flanges form a chamber for receiving the washers. Within this chamber the plate is provided with the slots 11 which are arranged in groups, shown in the plan view and the slots of each group are arranged according to the arrangement of nail holes in the heel. The slots lead to the curved tubes 12 which are suitably connected to the bottom of the plate. Each of these tubes is curved in such a manner as to hold the lowermost washer in a horizontal position directly over a pin. Each tube carries a spring plate 13 which has its lower end bent over the outlet end of the tube to prevent the washer from leaving said end. The bottom edge of said outlet end of each tube is recessed as at 14 to receive the pin and thus permit the washer to pass over said pin. The tubes may be split as shown though this is not necessary. In order to cause the washers to pass into the slots I provide rounded and peaked projections 15 on the upper face of the plate 8 around said slots.

As before stated, the plungers will hold the plate with the tubes holding the lowermost washers in a position directly over the pins so that when the plate is lowered said washers will pass on to said pins and rest upon the shoulders thereon. In order to lower said plate I provide a hand lever 16 pivoted on a shaft 17 carried by ears 18 on two of the side members of the frame, intermediate their ends and this lever is connected by the rods 19 to the levers 20 carried by the shafts 20' which are pivoted to the ears 21 located at the corners of the frame. At each end of each shaft is located an arm 22' which carries a roller 22, which engages with the upper face of the plate 8 at each corner thereof. The arms all extend

- 2 in the same direction so that when the lever is actuated said arms will be moved into a substantially vertical position so that the rollers thereon engaging the plate 8 will force the same downwardly thus depressing the plate so that the washers are placed over the pins. Lateral movement of the plate is prevented by its front edge engaging the flange on the frame. I provide means for holding the plate in its lowered position and these means consist of a dog 30 carried by the lever 16 and adapted to engage a notch quadrant 31. This dog is held in engagement with the notch by means of a spring 15 plunger 32 having one end connected with the dog and its other end engaging a guide 33 on the lever. After the plate is lowered it is moved rearwardly to release the washers from the tubes by means of a lever 20 23 secured on the shaft 17 and having its lower end connected by link 24 to lug 25 carried by the front of the plate. Thus when the lever 23 is actuated the plate 8 will slide rearwardly so that the washers on 25 the pins will be released from the ends of the tubes, the springs 13 being forced upwardly by said washers. As the lever 23 is moved it will rock the shaft 17 thus causing the cam 34 on said shaft to engage a plunger 30 35 which has its upper end connected with the dog 30. Thus the dog will be raised out of engagement with the notch to permit the parts to assume their normal raised position. Then the lever 23 may be returned to place 35 the plate in proper position for being lowered again. The device may then be lifted off the mold plate and placed on another one and the same operation carried out.
- 40 In this way a great number of groups of washers may be placed on the pins at the same time.
- It is thought from the foregoing description that the advantages and novel features 45 of our invention will be readily apparent.
- We desire it to be understood that we may make changes in the construction and in the combination and arrangement of the several parts, provided that such changes 50 fall within the scope of the appended claims.
- What we claim is:—
1. A device of the class described comprising a frame, a washer supporting plate supported thereby, curved tubes carried by 55 said plate and receiving the washers therefrom, spring carriers for holding the washers in said tubes, means for lowering the plate to place the washers on the pins and means for moving the plate laterally to release the washers from the tubes. 60
2. A device of the class described comprising a frame, a washer supporting plate carried thereby and having slots therein for the passage of the washers, projections for directing the washers into the slots, curved tubes connected with the bottom of the plate and communicating with the slots, spring latches holding the washers in the tubes, manually operated means for lowering the plate to place the lowermost washers in the tubes over the pins in the mold plate and means for moving the plate laterally to release said washers from the tubes. 65
- 70
3. A device of the class described comprising a frame, a washer supporting plate carried thereby and having slots therein, curved tubes connected to the bottom of the plate and communicating with said slots, spring latches for holding the washers in the tubes, means for lowering the plate for bringing the lowermost washers in the tubes over the pins in the mold plate and means for moving the plate laterally to release the washers from the tubes and at the same time release the lowering means. 75
- 80
4. A device of the class described comprising a frame, a washer supporting plate carried thereby, spring means for holding said plate in its raised position, washer delivery means carried by said plate, means for lowering the washer supporting plate to place the washers on the pins and means for moving the washer plate laterally to release the washers from the delivery means and at the same time release the lowering means. 85
- 90
5. In combination with a mold plate having recesses therein, a washer delivering device comprising a frame having depending legs for engaging said recesses, a movable plate in said frame, delivery tubes carried by said plate, means for delivering the washers to said tubes, means for lowering the washer plate to place the washers on the pins and means for moving the plate laterally to release said washers from the tubes. 100
- 105
- In testimony whereof we affix our signatures.
- BENJAMIN W. MARTIN.
HOMER SAMS.
